UNITED STATES PATENT OFFICE.

GEORGE A. HALL, OF DEXTER, MAINE, ASSIGNOR OF ONE-HALF TO EDWARD H. CHASE, OF SAME PLACE.

CARPET-STRETCHER.

SPECIFICATION forming part of Letters Patent No. 388,864, dated September 4, 1888.

Application filed March 29, 1888. Serial No. 268,739. (No model.)

To all whom it may concern:

Be it known that I, GEORGE A. HALL, a citizen of the United States, residing at Dexter, in the county of Penobscot and State of Maine, 5 have invented new and useful Improvements in Carpet-Stretchers, of which the following is a specification.

My invention relates to an improvement in carpet-stretchers; and it consists in the peculiar 10 construction and combination of devices that will be more fully set forth hereinafter, and particularly pointed out in the claims.

In the drawings, Figure 1 is a perspective view of a carpet-stretcher embodying my improvements. Fig. 2 is a vertical transverse 15 sectional view taken on the line xx of Fig. 1. Fig. 3 is a detail view of block G.

A represents a pair of parallel bars, which are connected at their front ends by a vertical 20 block, B. On the front side of the said block is screwed a plate, C, which is provided at its lower end with a pair of depending rearward-inclined engaging-prongs, D. One of the bars A is provided on its upper edge with a series 25 of ratchet-teeth, E.

F represents a roller, which is journaled between the rear end of bars A and is adapted to support the rear end of the machine.

G represents a block, which is arranged transversely under the bars A and projects laterally beyond the outer sides of the same. On 30 the upper sides of this block, at the center thereof, is secured a head, H, which is guided between the bars A and is adapted to slide 35 backward and forward between the same. Bolted to the upper side of this head is a plate, I, the sides of which extend laterally over the upper edges of the bars A and form flanges which serve to guide the head between the 40 bars and prevent the same from becoming dislodged therefrom. The said plate is provided at one of its rear corners with an ear, K, to which is pivoted a dog, L, that is adapted to engage the ratchet-teeth of one of the bars. 45 The said dog has an operating-handle, M, which is provided at its outer end with a weight, N.

O represents a pair of links, which have 50 their lower ends pivoted on the inner side of the bars A, near the rear ends thereof.

P represents an operating-lever, which has its lower front ends pivoted to the rear end of the head H, and said operating-lever is connected to the links O by means of a pivotal bolt, R. At the outer end of the operating-lever is a handle, S, by means of which the lever may be readily operated.

On the under side of the block G, near the end and at the center thereof, are secured 60 cushions or plates T, which are made of leather or other suitable elastic material. The length of the said cushions or plates is somewhat in excess of the width of the block G, and the ends of said cushions or plates are rigidly secured to the bottom of said blocks and flush 65 with the front and rear sides thereof, and thereby said cushions or plates are bowed downward from the said blocks and are rendered resilient or yielding, as will be readily understood.

U represents a series of engaging-teeth with which each of the yielding plates or cushions is provided, the said teeth being made of steel or other suitable material, U-shaped, having their lower ends beveled and passed through 75 openings in the said plates, and having their upper sides bearing on the block G, as shown in Fig. 3.

The operation of my invention is as follows: The prongs D are caused to engage the floor at 80 the wainscoting of the room, the lever P is turned to nearly a vertical position, so as to draw the block G inward on the bars A, and the teeth on the lower sides of the yielding plates of said block are caused to engage the 85 edge of the carpet. The operator then depresses the rear end of the lever T, and thereby forces the block G forward, so as to cause the same to effectually stretch the carpet. The dog which engages the ratchet-teeth on one of 90 the bars prevents retrograde movement of the block and serves to maintain the carpet in position when stretched while the same is being tacked to the floor. The plates T being resilient, compensate for any unevenness of the 95 floor on which the carpet is being laid and permit the teeth on said plates to yield and move vertically when the edge of the carpet to which they engage encounters a projection or rough place on the floor, so as to cause the 100

carpet to slide over the same and thereby prevent the carpet from being arrested at such places.

Having thus described my invention, I 5 claim—

1. The combination, in a carpet-stretcher, of the bars A, having the prongs at their front ends and the supporting roller at their rear ends, the block having the engaging-teeth and 10 provided with the head arranged between the bars and guided therein, the lever pivoted to the said head, and the links O, connecting the lever to the bars A, substantially as described.
2. The combination of the bars A, having 15 the ratchet-teeth, the block at the front ends of the said bars having the engaging-prongs,

the roller journaled between the rear ends of the bars, the block having the head arranged between the bars A, the plate secured on the said head and having the flanges bearing on 20 the upper sides of the bars, the dogs pivoted to the said plate and adapted to engage the ratchet-teeth, the lever pivoted to the block, and the links connecting the lever to the bars A, substantially as described. 25

In testimony that I claim the foregoing as my own I have hereto affixed my signature in presence of two witnesses.

GEORGE A. HALL.
